(57) **CLAIM**

The ornamental design for surface ornamentation for caskets, as shown and described.

DESCRIPTION

FIG. 1 is a perspective view of our new, original and ornamental design for surface ornamentation for caskets; FIG. 2 is a top view thereof;

FIG. 3 is a top view of an alternative embodiment thereof; FIG. 4 is a top view of an alternative embodiment thereof; and,

FIG. 5 is a top view of an alternative embodiment thereof. The broken line showing of the casket is for illustrative purposes only and forms no part of the claimed design. The depicted contrast in shading represents a contrast in appearance via color, texture, material and/or luminance.
